REGISTERING APPARATUS

Earl A. Keeler, Norristown, Pa., assignor to The Brown Instrument Company, Philadelphia, Pa., a corporation of Pennsylvania

Application November 23, 1938, Serial No. 241,996

13 Claims. (Cl. 177—311)

This invention relates to the detection of broken filaments in a thread.

The present invention is a continuation in part of my prior application Serial No. 118,095, filed December 29, 1936, now Patent 2,188,754, January 30, 1940, which discloses various arrangements for detecting defective filaments in a thread together with means actuated thereby for indicating and/or recording the number of such imperfections.

The various arrangements disclosed in my prior application were devised by me with the general object in view of providing simple and efficient means for detecting defective filaments in a single thread or in a plurality of threads together with means actuated thereby for indicating the presence and/or recording the number of such imperfections.

The apparatus claimed herein is an arrangement embodying my invention in which the moving thread is charged to a suitable potential and then passed through a loop of the proper clearance to permit defective filaments to touch the loop and thereby impart a charge to the latter, which charge may be utilized to control, through a sensitive electrical circuit, recording or indicating means.

In one specific embodiment of the invention repeated impacts of thread defects on the loop referred to above may be employed to charge a condenser and to thereby provide a basis for measurement of the number of thread defects by a totalizing discharge method to be described.

In the manufacture of fabrics from rayon or other threads the presence of defective filaments in the individual threads shows up in the finished material in the form of fuzzy ends. Heretofore in order to eliminate these fuzzy ends provisions have been made for the inspection by observation of a portion of the thread during transfer of the thread from spool to spool and rejection of any spools having an excessive number of broken filaments. This inspection operation is obviously expensive and, more important from the standpoint of producing quality material, is inadequate by virtue of the fact that only a small portion of the total output can practicably be inspected.

Moreover, visual inspection of the thread during transfer of the thread from spool to spool and detection of broken filaments is difficult as will be readily appreciated when it is understood that rayon threads which themselves are extremely small in diameter are made up from 40 to 100 or more of such filaments. By means of

the arrangement claimed herein, the manual inspection operation referred to may be dispensed with and defective thread filaments may automatically be detected and indicated by readily distinguishable means.

As a means for such automatic detection, I employ suitable means arranged in the path of the thread, as the latter is being transferred from spool to spool, for applying an electrical charge to the thread and thereafter collecting part of said charge from the fuzzy or broken filaments. The electrical charge so collected is employed to control a sensitive electrical circuit and thereby the energization of suitable indicating means to be described. Thus, an indication of the presence of broken filaments of the thread, which are difficult of detection by visual means alone, may be had.

The various features of novelty which characterize my invention are pointed out with particularity in the claims annexed to and forming a part of this specification. For a better understanding of the invention, however, its advantages and specific objects attained with its use, reference should be had to the accompanying drawing and descriptive matter in which I have illustrated and described a preferred embodiment of the invention.

Of the drawing:

30 Fig. 1 is a more or less diagrammatical view illustrating one form of the invention;

Fig. 2 illustrates a modification of the registering device of Fig. 1;

Fig. 3 is a wiring diagram illustrating a modification of the arrangement of Fig. 1; and

Fig. 4 is a modification of the device of Fig. 3.

Referring to Fig. 1, provision is made, as illustrated, for arranging a detector 1 in the path of the moving thread for detecting the presence of broken filaments in the thread. Normally in practice, the detector may desirably be arranged in the path of the thread as it is being unwound from a spindle on a spinning machine and wound on a bobbin immediately after the spinning operation. For clarity and definiteness of illustration, however, I have shown, in a more or less diagrammatic way, the thread 2 as being unwound from a spool 3 and reeled on a spool 4, the latter being mounted for rotation on a shaft 5 driven through suitable gearing, not shown, by a unidirectional electrical motor 6 energized for rotation from alternating current supply lines L^1 and L^2 . The spool 3 is mounted for rotation on a shaft 7 which may be disposed on suitable brackets 8 in any convenient manner. Preferably both

spools 3 and 4 are so mounted for rotation as to facilitate quick removal and replacement by other spools.

The detector 1 includes an electrical conductor 9 arranged in the path of the thread and having a loop 10 at its upper end through which the thread is passed, and which is adapted to receive an electrical charge from the thread when broken filaments engage the said loop. The thread is guided into the loop 10 by guide rods 11 and 12 10 having saddle portions at their upper end for guiding the thread. The charge so imparted to the loop 10 and hence to the conductor 9 is employed to control a sensitive electrical circuit to thereby indicate and/or record the imperfections 15 in the thread.

As illustrated, means are provided in the form of an electronic circuit 13 for imparting a charge to the moving thread 2 immediately before it passes through the loop 10 and for indicating 20 when part of the charge is imparted to the loop by defective thread filaments. This electronic circuit includes a rectifier circuit which is capable of delivering a high direct current potential, the positive side of which is connected by a conductor 14 to a brush 15, the latter being in engagement with the moving thread 2 and adapted to impart a charge thereon. The rectifier is energized from secondary windings 16 and 17 of a transformer 18, the primary winding 19 of which is energized from the alternating current supply lines L¹ and L². Secondary windings 20 and 21 are also disposed on the transformer 18 and are employed for supplying current for heating the filament and for supplying anode voltage to a three-electrode electronic tube 22, respectively. The tube 22 includes the usual cathode 23, anode 24, and grid 25, the latter being connected to the conductor 9. A relay winding 26 is connected in the plate circuit of the tube 22 and is adapted to operate an armature 27 to close a circuit through a neon tube 28 connected through a resistance 29 to the alternating current supply lines L³ and L⁴.

In operation the tube 22 is normally non-conductive, but when a positive charge is imparted to the grid 25 as a result of engagement of a defective filament with the loop 10, the tube will become conductive during the half cycle when the anode 24 is positive. The resulting flow of pulsating current through the relay winding 26 will energize the latter to thereby effect the closure of the energizing circuit to the neon tube 28. Thus, the presence of the thread imperfection will be indicated by glowing of the tube 28.

If desired, a permanent record of the presence of the thread imperfection may be had and in Fig. 2 I have illustrated one means for obtaining such a record. As illustrated, the relay winding 26 arranged in the output circuit of tube 22 may be adapted to actuate a marker lever 30 which is pivoted at one end on a shaft 31. A print hammer 32 disposed on the other end of lever 30, is adapted to strike a recorder chart 33 through a suitable ribbon 34 and to thereby make a mark on the recorder chart each time that the relay winding 26 is energized. The lever 30 is normally biased for rotation in a clockwise direction by spring means 35 into engagement with a stop 36 so that when the relay winding 26 is deenergized, the print hammer 32 is held out of engagement with the recorder chart 33 and ribbon 34. The recorder chart is adapted to be driven by a continuously rotating roller 37, the latter being driven in any convenient manner, as for example, by a unidirectional electrical motor 38 through

suitable gearing 39 so that any imperfections of the thread will be recorded on the chart as a series of contiguous marks on a straight line.

As illustrated in Fig. 2, provision may advantageously be made for recording the imperfections in a plurality of threads simultaneously on a single recorder chart 33. For so recording the imperfections in a number of threads simultaneously, separate detector means 1 are arranged in the path of the individual threads, the said detectors being adapted to control a plurality of electronic circuits 13, each of the latter having a relay winding 26 disposed in the output circuits thereof and associated elements 30, 32, 33 and 34. As will be readily understood, the number of threads which may practicably be simultaneously inspected in this manner is limited only by the width of the chart employed. Print hammers may conveniently be spaced at a small distance, say an eighth of an inch apart, and hence fifty or a hundred threads may simultaneously be inspected and a record of imperfections thereof had on a single record chart. For convenience in scanning the chart and noting the number of imperfections in any of the threads inspected by such a multiple unit, provision has been made in the form of a guide 40 disposed parallel to the chart roll 37, in close proximity therewith and slightly below the level of the print hammers. A sighting slide 41, having a slot 42 running lengthwise, is disposed at right angles to the guide 40 and is adapted to cooperate at its upper end with the latter so as to be manually slidable along the chart, and the marks in any single line may be seen through the slot 42. Preferably, each print hammer is consecutively numbered in either direction as desired, on the guide 40, and the slot 42 extended so that the number may be seen therethrough, or a separate opening may be provided for this purpose, as desired. In this manner the marks denoting imperfections for any single thread may be scanned individually, in that the marks pertaining to other threads simultaneously inspected and in close proximity to those it is desired to scan are excluded from view and thereby precludes any confusion which might otherwise result in scanning the chart.

In Fig. 3 I have illustrated another embodiment of my invention in which repeated engagements of defective thread filaments with the loop 10 are employed to charge a condenser 43 the latter being periodically discharged and the discharge current measured in any suitable manner. In this embodiment the thread 2 is shown as receiving a charge from the positive terminal of a battery 44 through a conductor 45 connected to the brush 15, but it will be understood a rectifier arrangement as disclosed in Fig. 1 may be employed in lieu of the battery, if desired. On engagement of defective thread filaments with the loop 10, part of the charge on the thread will be transferred to the condenser 43, and as will become apparent, the magnitude of the charge stored on the condenser will depend upon the number of such engagements and hence, upon the number of imperfections in the thread. Periodically, the condenser 43 is discharged by closure of a switch 46, which switch may be actuated by means of any suitable time actuated mechanism. Preferably, I employ intermittently operating discharge means providing equal intervals of time between each discharge period, which discharge means as diagrammatically shown, includes a cam 47 driven by a continuously rotating shaft 48 for operating switch 46 alternately to its open

and closed positions. The discharge current may be measured in any convenient manner, as for example, by a hot wire or other suitable current measuring instrument 49. As will be apparent, the magnitude of the discharge current will be a measure of the number of engagements of thread defects with the loop 10 occurring in the interval that the switch 46 is open.

In Fig. 4 I have shown a modification of the embodiment of my invention described in Fig. 3 in which repeated engagements of thread defects with the loop 10 are employed to charge a condenser 50, the latter being automatically discharged when the charge stored up exceeds a certain predetermined value. This discharge current is employed to control the flow of anode current in an electronic device 51 to thereby effect indication, and if desired, recording, each time a predetermined number of engagements of thread defects with the loop 10 have occurred.

The electronic device 51 includes a transformer 52, having secondary windings 53, 54, 55, and a primary winding 56 energized directly from the alternating current supply lines L¹ and L². The secondary windings 53 and 55 supply current for heating the filaments of electronic tubes 57 and 58, and the winding 54 supplies anode voltage to the tube 57. The tube 57 is a full wave rectifier tube, the rectified voltage being impressed on the anode circuit of the triode 58. A condenser 59 and a divider resistor 60 are employed in the usual manner for smoothing out alternating current ripples in the rectified voltage. A point on the divider resistor 60 at a suitably high potential is connected by a conductor 61 to the brush 15 for imparting a charge to the thread, a portion of which charge is adapted to be transferred to the condenser 50 by a conductor 62 each time defective thread filaments engage the loop 10.

The tube 58 is a heater type tube and is comprised of the usual cathode 63, anode 64, and grid 65, the latter being connected through a resistor 66 to the negative terminal of divider resistor 60. Negative bias is provided for the grid 65 by means of a resistor 67 connected in the cathode circuit so that normally the tube is non-conductive. A gaseous discharge tube 68 is connected by conductors 69 and 70 between the grid 65 and the conductor 62. This tube 68 has a current-voltage characteristic such that up to a certain voltage across the tube no current flows, but when the striking potential is reached, a discharge passes and the voltage across the tube drops and becomes quite constant regardless of the current taken from the tube. When the charge accumulated on the condenser 50, as a result of repeated engagements of thread defects on the loop 10 exceeds a predetermined value, a discharge passes between the elements in the tube 68 and through the resistor 66 back to the other plate of the condenser. The potential difference momentarily maintained across the resistor 66 by the discharge current reduces the negative bias on the grid 65 to thereby render the tube 58 conductive. The anode current conducted by the tube may be employed in any suitable manner to afford indication and, if desired, to effect a recording operation each time that a predetermined number of engagements of thread defects with the loop 10 have occurred.

As shown in Fig. 4, a lamp 71 connected in the anode circuit of the tube 58 is provided for indicating whenever a predetermined number of fuzz projections have passed the loop 10. In-

tegrating means 72 have also been provided for recording the number of such imperfections. The means 72 may advantageously be actuated by a relay 73 connected in parallel or in series, as desired, with the lamp 71. An armature 74 pivoted for rotation at 75 and biased for rotation in a clockwise direction by spring means 76 is disposed in inductive relation to the relay 73 so that when the latter is energized the armature will be rotated counterclockwise into engagement with the relay. The armature 74 is connected by means of a link 77 to one end of a lever 78 pivoted for rotation at the other end on a shaft 79 and carrying a pawl 80 intermediate its ends. This pawl 80 is adapted to cooperate with a ratchet wheel 81 also mounted for rotation on the shaft 79. A gear 82 integral with the ratchet wheel 81 is adapted to cooperate with a gear 83 connected in any suitable manner to a counter 84 so that rotation of the ratchet wheel 81, as a result of energization of the relay 73, results in actuation of the counter to thereby record the total number of engagements of fuzz projections with the loop 10. It is not to be construed, however, that the embodiment of the invention described in Fig. 4 is limited to the recording means shown, for any suitable recording means may be employed, as for example, described elsewhere herein.

While in accordance with the provisions of the statutes, I have illustrated and described the best form of my invention now known to me, it will be apparent to those skilled in the art that certain changes may be made in the form of the apparatus disclosed without departing from the spirit of my invention as set forth in the appended claims, and that certain features of my invention may sometimes be used to advantage without a corresponding use of other features.

Having now described my invention what I claim as new and desire to secure by Letters Patent is:

1. In apparatus to indicate a variable characteristic of an electrical non-conducting body, means to place an electrical charge on the body, a device normally out of physical contact with but disposed in cooperative relation with the body and adapted to receive a charge therefrom in accordance with variations in said characteristic, and electronic valve means connected to said device and responsive to the charge thereon to indicate the variations in said characteristic.

2. In apparatus to indicate a variable characteristic of an electrically non-conducting body, a source of electric potential, means connecting said source to impart an electrical charge to said body, a device normally out of physical contact with but disposed in cooperative relation with the body and adapted to receive a charge therefrom in accordance with variations in said characteristic, electronic valve means, current responsive means connected to said valve means to indicate the said variations in said characteristic, and means connected to said device and responsive to the charge thereon to control the flow of electric current through said valve.

3. The method of detecting defective filaments projecting from an electrically non-conducting thread including the steps of applying an electrical charge to the thread, collecting the charge from the defective filaments, and measuring said charge.

4. Apparatus for detecting defective filaments projecting from an electrically non-conducting thread including means for imparting an elec-

trical charge to the thread, means normally out of contact with said thread and engaged by said defective filaments for collecting said charge, and a device operated by the second mentioned means upon engagement therewith of said filaments.

5. In apparatus for detecting defective filaments projecting from an electrical non-conducting thread, an electronic valve including an anode, a control electrode and a cathode, means for applying an electrical charge to said thread, detecting means disposed in cooperative relation with said thread, means for relatively moving said thread and detecting means for imparting at least a portion or all of said electrical charge to said detecting means under control of said defective filaments, means connected to said control electrode responsive to the electrical charge collected by said detecting means for controlling the flow of electric current through said valve, and means responsive to said electric current for indicating whenever a charge is imparted to said detecting means.

6. In apparatus for ascertaining the number of imperfections in a thread due to defective filaments, a source of voltage, a condenser, detecting means disposed in cooperative relation with said thread, means for relatively moving said thread and detecting means, said detecting means including means to momentarily connect said source of voltage to said condenser under control of said filaments for imparting a charge to said condenser, periodically operated means for discharging said condenser, and means for measuring the discharge current.

7. In apparatus for ascertaining the number of imperfections in a thread due to defective filaments, a condenser, an electronic valve comprising an anode and a cathode, a source of direct current voltage for said condenser and said valve, a gaseous discharge tube, detecting means disposed in cooperative relation with said thread, means for relatively moving said thread and detecting means to cause impact of defective filaments with said detecting means and thereby impart an electric charge to said condenser from said direct current voltage source, the said gaseous discharge tube being adapted to discharge said condenser when a predetermined number of electric charges have been applied to the latter, means responsive to the discharge current for controlling the flow of electric current through said valve, and means responsive to said electric current for indicating each such discharge.

8. In apparatus for ascertaining the number of imperfections in a thread due to defective filaments, a condenser, an electronic valve comprising an anode, grid, and a cathode, a source of direct current voltage for said condenser and said valve, an electrical resistance, a gaseous discharge tube connected in series with the resistance and both of the latter shunting said condenser, the said gaseous discharge tube having a current-voltage characteristic such that up to a certain critical voltage applied thereon, it is non-conductive and at the critical voltage becomes conductive, detecting means disposed in cooperative relation with the thread, means for relatively moving said thread and detecting means to cause engagement of defective filaments with said detecting means for connecting said direct current voltage to said condenser for imparting an electrical charge on the latter, the said gaseous discharge tube being adapted to discharge said condenser through said resistance when a predetermined number of electric charges have been applied to the condenser for producing a voltage drop across said resistance to control the flow of anode current through said valve, and means disposed in the anode circuit of said valve for indicating whenever a predetermined number of engagements of defective filaments with said detecting means have occurred.

9. In apparatus to indicate a size variation of an electrical non-conducting body, means to place an electrical charge on the body, a device normally out of physical contact with but disposed in cooperative relation with the body and adapted to receive a charge therefrom by contact of said device and said body upon variation in size of said body, and electronic valve means connected to said device and responsive to the charge thereon to indicate the variations in size of said body.

10. In apparatus for ascertaining the number of imperfections in a thread due to defective filaments projecting from the thread, a source of voltage, a condenser, detecting means disposed in cooperative relation with said thread, means for relatively moving said thread and detecting means, said detecting means including means to impart an electrical charge from said source of voltage to said thread and means adapted to contact said projecting filaments to collect said charge and to impart a charge to said condenser, intermittently operated means for discharging said condenser, and means for measuring the discharge current.

11. In apparatus for ascertaining the number of imperfections in an electrically non-conducting thread due to defective filaments projecting from the thread, a source of voltage, a condenser, detecting means disposed in cooperative relation with said thread, means for relatively moving said thread and detecting means, said detecting means including means to impart an electrical charge from said source of voltage to said thread and means adapted to contact said projecting filaments to collect said charge and to impart a charge to said condenser, intermittently operated means for discharging said condenser, and means for measuring the discharge current.

12. In apparatus for ascertaining the number of imperfections in a thread due to defective filaments projecting from said thread, a condenser, an electronic valve comprising an anode and a cathode, a source of direct current voltage, detecting means disposed in cooperative relation with said thread, means for relatively moving said thread and detecting means, said detecting means including means to impart an electrical charge from said source of voltage to said thread and means adapted to contact said projecting filaments to collect said charge and to impart a charge to said condenser, a gaseous discharge tube to discharge said condenser when a predetermined number of electric charges have been applied to said condenser, means responsive to the discharge current for controlling the flow of electric current through said valve, and means responsive to said electric current for indicating each such discharge.

13. In apparatus for ascertaining the number of imperfections in a thread due to defective filaments, a condenser, an electronic valve comprising an anode, grid, and a cathode, a source of direct current voltage, an electrical resistance, a gaseous discharge tube connected in series with said resistance and both of the latter shunting said condenser, the said gaseous discharge tube having a current-voltage characteristic such that up to a certain critical voltage applied thereon, it is non-conductive and at the critical voltage becomes conductive, detecting means disposed in cooperative relation with the thread, means for relatively moving said thread and detecting means to cause engagement of defective filaments with said detecting means for connecting said direct current voltage to said condenser for imparting an electrical charge on the latter, the said gaseous discharge tube being adapted to discharge said condenser through said resistance when a predetermined number of electric charges have been applied to the condenser for producing a voltage drop across said resistance to control the flow of anode current through said valve, and means disposed in the anode circuit of said valve for indicating whenever a predetermined number of engagements of defective filaments with said detecting means have occurred.

14. In apparatus for ascertaining the number of imperfections in a thread due to defective filaments, a condenser, an electronic valve comprising an anode, grid, and a cathode, a source of direct current voltage, an electrical resistance, a gaseous discharge tube connected in series with said resistance and both of the latter shunting said condenser, the said gaseous discharge tube having a current-voltage characteristic such that up to a certain critical voltage applied thereon, it is non-conductive and at the critical voltage becomes conductive, detecting means disposed in cooperative relation with the thread, means for relatively moving said thread and detecting means to cause engagement of defective filaments with said detecting means for connecting said direct current voltage to said condenser for imparting an electrical charge on the latter, the said gaseous discharge tube being adapted to discharge said condenser through said resistance when a predetermined number of electric charges have been applied to the condenser for producing a voltage drop across said resistance to control the flow of anode current through said valve, and means disposed in the anode circuit of said valve for indicating whenever a predetermined number of engagements of defective filaments with said detecting means have occurred.

having a current-voltage characteristic such that up to a certain critical voltage applied thereon it is non-conductive and at the critical voltage becomes conductive, detecting means disposed in cooperative relation with the thread, means for relatively moving said thread and detecting means, said detecting means including means to impart an electrical charge from said source of voltage to said thread and means adapted to contact said projecting filaments and collect said 10 charge and to impart a charge to said condenser,

the said gaseous discharge tube being adapted to discharge said condenser through said resistance when a predetermined number of electrical charges have been applied to the condenser for producing a voltage drop across said resistance to control the flow of anode current through said valve, and means disposed in the anode circuit of said valve for indicating whenever a predetermined number of defective filaments have contacted said detecting means.

EARL A. KEELER.
